(57) CLAIM

The ornamental design for a light hoop, as shown and described.

DESCRIPTION

FIG. 1 is a front isometric view of a light hoop.

FIG. 2 is a front elevation view thereof.

FIG. 3 is a back elevation view thereof.

FIG. 4 is a right side elevation view thereof.

FIG. 5 is a left side elevation view thereof as viewed from the section plane 5-5 in FIG. 2.

FIG. 6 is a top plan view thereof; and,

FIG. 7 is a bottom plan view thereof.

The stippling indicates a change in material and the oblique line shading indicates translucent material. The broken lines are for environmental purposes only and form no part of the claimed design.
